UNITED STATES PATENT OFFICE.

ELIJAH J. B. WHITAKER, OF NEW YORK, N. Y.

POP-GUN.

SPECIFICATION forming part of Letters Patent No. 302,367, dated July 22, 1884.

Application filed February 8, 1884. (No model.)

To all whom it may concern:

Be it known that I, ELIJAH J. B. WHITAKER, residing in the city, county, and State of New York, have invented a new and useful Improvement 5 in Pop-Guns; and I do hereby declare that the following is a full and exact description thereof, reference being had to the accompanying drawings, and to the letters of reference marked thereon, making a part of this 10 specification.

My invention relates to a simple pop-gun, designed as a child's toy.

It consists in uniting the outer plug or stopper for the tube with its plunger by a flexible 15 connection of such length as that when the plunger is drawn back into the tube far enough to produce by its forward movement the required compression of air it shall operate automatically to seat the plug in the mouth of the tube 20 tightly enough to permit of such compression.

It consists, furthermore, in fitting to the inner end of the tube a second plug or stopper, mounted to slide freely on the stem of the plunger, and adapted to be driven to its seat in the 25 tube by the forward movement of the plunger, so as to be forcibly expelled therefrom by the compression of the air produced by the backward movement of the plunger.

In the accompanying drawings, Figure 1 is 30 a longitudinal sectional view of my improved pop-gun when ready for action to discharge its front stopper; Fig. 2, a similar view illustrating the device in readiness for action to produce a discharge of the rear stopper. Figs. 35 3 and 4 illustrate modifications of the invention.

A represents the open-ended tube of the pop-gun, which may be of any suitable description, of any suitable material, and of any desirable 40 outward configuration. Within the tube is fitted in the customary manner a piston or plunger, B, adapted to traverse freely therein with as nearly as possible an air-tight joint. This plunger B is actuated in the customary 45 manner by a rod, C, secured centrally thereto, and which is of such length as that it will extend out far enough from the rear end of the tube, when the plunger is near to its forward end, to receive a suitable handle, D, or otherwise furnish a proper hold for the operator. 50 A plug or stopper, E, is made to fit securely into the front end of the tube, and for this purpose

it is preferably made of cork or other elastic material and of a slightly tapering form, so that it shall enter and wedge closely into its 55 seat. A similar plug or stopper, E', is fitted into the rear end of the tube, and is centrally perforated to admit of the passage through it of the plunger-rod C with as nearly as possible an air-tight joint. The front stopper, E, is 60 firmly connected to the front end of the plunger B by a strong flexible cord, F, of such length as that when the plunger is drawn back to the rear end of the tube into close proximity to the seat for the rear stopper, E', as shown 65 in Fig. 1, the front stopper, E, will be thereby automatically drawn and fitted into its seat, and the plunger arrested, so that it may not be withdrawn entirely from the tube. The stopper is arrested, when it becomes properly 70 seated, by means of a shoulder or an offset, h, on its front end, and which may be formed by an outer overlapping plate, G. (See Fig. 2.) The rear stopper, E', moves freely upon the rod C, and is driven into its seat in the rear 75 of the tube, when the plunger B is pushed inward into proximity to the seat for the front stopper, E, (as shown in Fig. 2,) by means of a shoulder or an offset, i, of any suitable description, formed upon the rod, this shoulder or off-set serving also as a stop to prevent the plunger from passing too far into the tube. 80

As an equivalent for the flexible cord F, to couple the plunger B with the stopper E, I contemplate the use of two wires, S S, Fig. 3, 85 secured firmly to the plug and adapted to pass freely through the plunger, their entire withdrawal being prevented by stops on their outer ends, so that the plunger and stopper shall have free movement independent of each other, 90 except so far as limited by the length of said wires; or a single inflexible rod or wire, T, Fig. 4, may be used to project centrally from the plunger B in a right line with or as an extension of its rod C, and play freely through 95 the stopper E with an air-tight joint, the withdrawal of the stopper therefrom being prevented by a stop on the end of said extension-rod T.

Although I have described the automatic 100 pop-gun as constructed with a rear stopper, E', to act as an auxiliary to the front stopper, E, and so make the pop-gun double-acting, it is evident that my invention is applicable to

a single-acting pop-gun working with but a single plug or stopper, E.

In the use of the device, when the plunger B is drawn back to its full extent into the tube 5 A, the front stopper, E, is thereby drawn into its seat, plugging and closing completely the front end of the tube. If now the plunger be pushed forcibly forward, the body of air confined between the plunger and stopper will be 10 compressed until the frictional contact of the stopper with the tube is overcome and the stopper violently expelled, the expansion of the compressed air thereby released producing a loud report. As the plunger is thus 15 pushed forward to expel the front stopper, E, the rear stopper, E', will be carried to its seat by the shoulder *i* of the handle, thus closing the rear end of the tube, so that as the plunger is drawn back the air compressed between 20 it and said rear stopper is in turn compressed to produce its expulsion and a second loud report. As the front stopper becomes seated by this movement of the plunger, the gun is charged in readiness for a repetition of the first 25 movement, and by a quick movement of the plunger back and forth a constant succession of loud explosive reports may be very rapidly produced.

I claim as my invention--

1. A self-charging pop-gun consisting of an 30 open ended tube, a plunger working in said tube, a plug or stopper adapted to close one end thereof, and a cord or rod coupling the stopper with the plunger and permitting a limited independent movement of the two, 35 substantially in the manner and for the purpose herein set forth.

2. A double-acting self-charging pop-gun consisting of an open-ended tube, a plunger working in said tube, a rod actuating said plunger and extending out from one end of the tube, a plug or stopper moving upon said rod and adapted to close the end of the tube and to be driven to its seat by an offset or shoulder on the rod, and a second plug or 45 stopper adapted to close the opposite end of the tube, and which is coupled to the plunger by a cord or rod permitting a limited independent movement of the two, all substantially in the manner and for the purpose here- 50 in set forth.

In testimony whereof I have signed my name to this specification in the presence of two subscribing witnesses.

E. J. B. WHITAKER.
